UNITED STATES PATENT OFFICE.

JOHN LUTZ AND CHARLES J. LEYES, OF JERSEY CITY, NEW JERSEY, ASSIGNEES, BY
DIRECT AND MESNE ASSIGNMENTS, TO THE RAPID DISPLAY MACHINE COMPANY,
OF JERSEY CITY, NEW JERSEY, A CORPORATION OF NEW JERSEY.

APPARATUS OR MACHINE FOR EXHIBITING RUGS.

1,069,966.

Specification of Letters Patent.

Patented Aug. 12, 1913.

Application filed August 8, 1912, Serial No. 713,993. Renewed June 28, 1913. Serial No. 776,397.

To all whom it may concern:

Be it known that we, JOHN LUTZ and CHARLES J. LEYES, citizens of the United States, and residing at Jersey City, in the county of Hudson and State of New Jersey, have invented certain new and useful Improvements in Apparatus or Machines for Exhibiting Rugs, of which the following is a specification, such as will enable those skilled in the art to which it appertains to make and use the same.

This invention relates to apparatus or machines for exhibiting or displaying rugs to purchasers, and the object thereof is to provide an improved apparatus or machine of this class which is designed for use by dealers in rugs, carpets and like articles for the purpose of displaying their merchandise, and particularly for the purpose of displaying rugs in a horizontal position.

The invention is fully disclosed in the following specification, of which the accompanying drawing forms a part, in which the separate parts of our improvement are designated by suitable reference characters in each of the views, and in which:

Figure 1 is a side view of our improved machine; Fig. 2 a plan view thereof with part of the structure broken away; and, Fig. 3 an end view looking in the direction of the arrow α but showing only part of the machine.

In the practice of our invention, we provide a base board or table a having short legs a^2 and provided at each end with upright supports b in which are mounted rollers b^2 and b^3 . Arranged centrally of the table a are bow-springs c , each of which is provided with an upwardly directed ear c^2 with which is connected a rock table c^3 provided centrally of its underside with two pairs of ears c^4 , which correspond with the ears c^2 , and the springs c are provided in their ends with longitudinal slots c^5 and passed therethrough into the table a are screws or bolts c^6 , and this construction permits of a slight longitudinal movement of the ends of the spring c .

Arranged centrally of and beneath the end portion of the rock table c^3 over which the roller b^2 is mounted is a support d secured to the table a , and in the top of which is pivoted a crank lever d^2 with which is connected a link d^3 which is pivoted to the

bottom of the rock table c at d^4 , and connected with the longer arm of the crank lever d^2 is a rod d^5 which extends longitudinally of the table a to about the middle thereof, and which is connected at d^6 with a plate d^7 mounted centrally on and movable longitudinally of the table a . One end of the plate d^7 is provided with a longitudinal slot d^8 through which are passed screws or similar devices d^9 which connect the plate d^7 with the table a , while permitting of its longitudinal movement on said table.

The plate d^7 is provided with a backwardly directed arm e , the outer end of which is forked as shown at e^2 , and secured near the opposite end portions of the table a and at the back edge thereof are supports e^3 in which is mounted a shaft e^4 which extends parallel with the back edge of the table a and which is provided centrally thereof with a disk or annular shoulder e^5 which fits in the forked end e^2 of the arm e .

The shaft e^4 is provided at its opposite ends with friction gears e^6 and e^7 , and mounted transversely of and over the outer end portions of the table a are shafts f and f^2 having sprocket gears f^3 and f^4 , and the rollers b^2 and b^3 are provided with corresponding gears f^5 and f^6 , and drive chains f^7 and f^8 are mounted respectively on the gears f^3 and f^5 , and f^4 and f^6 .

The shafts f and f^2 are provided at the back side of the table a with large friction gears g and g^2 in connection with which the gears e^6 and e^7 of the shaft e^4 operate, and the gears g and g^2 are movable longitudinally on the shafts f and f^2 , and mounted beneath the opposite end portions of the table a and movable transversely thereof are bars h and i which are provided at their back ends respectively with upwardly directed forks h^1 and i^1 which engage the hubs of the gears g and g^2 and are adapted to move said gears longitudinally of the shafts on which they are mounted, and the bar h is provided at its front end with a downwardly directed arm h^2 which is connected with a crank lever h^3 secured to a rock shaft j supported at the front of the table a as shown at j^2 .

The bar i is provided at its front end with an upwardly directed arm i^2 which is connected with an upwardly directed crank i^3 secured to the shaft j , and secured to the

shaft j near one end of the table a is a lever k for rotating or rocking the shaft j and for shifting the gears g and g^2 on the shafts f and f^2 .

5 The shaft e^4 which is the main power shaft of the machine may be turned in any desired manner, but in the accompanying drawing we have shown an electric motor m for this purpose. The shaft m^2 of the 10 motor m is provided with a gear m^3 which meshes with a corresponding gear m^4 mounted on a shaft m^5 having supports m^6 , and the shaft m^5 is provided with an elongated gear m^7 which operates in connection with a 15 gear m^8 mounted on and secured to the shaft e^4 .

The rock table c^3 is provided at its opposite ends with a roll or cylindrical formation as shown at n and, in practice, a wide belt 20 or strip o of any suitable material is wound on one of the rollers b^2-b^3 and connected with the other, and, in practice, the rugs o^2 to be exhibited are placed on the belt or strip o , which is wound on one of the rollers 25 b^2-b^3 , the roller b^2 being employed in this case. With this construction when it is desired to exhibit the rugs, the machine is put in operation and the roller b^3 is slowly wound or turned in the direction of the 30 arrow y , and as the roller b^3 is turned in this manner, the belt or strip o will be drawn from the roller b^2 and rewound on the roller b^3 , and in this operation the rugs o^2 will successively pass over the rock table c^3 and 35 may be clearly seen and examined as will be readily understood.

The opposite end portions of the rock table c^3 bear on the undersides of the rollers b^2-b^3 in the above operation and as the 40 strip or belt o and the rugs are rewound from one of said rollers onto the other, one end of the rock table c^3 will go down and the other up, as will be readily understood, and one of the objects of the springs c is to 45 regulate the pressure of the end portions of the rock plate c^3 on the bottoms of the rollers b^2 and b^3 , and to keep the said rollers and especially that from which the belt or strip o and rugs are being unwound from racing 50 or turning too freely.

It will be understood that the gears g and g^2 are secured to and not rotatable on the shafts f and f^2 , and supposing the parts to be in the position shown and it is desired to 55 start the machine, the lever k is manipulated so as to rock the shaft j and throw the gears g and g^2 into the dotted line position shown in Fig. 2, in which position the gear e^7 on the shaft e^4 will engage the gear g^2 on the 60 shaft f^2 . Suppose now the motor m to be in operation, the shaft e^4 will be rotated and the gear e^7 engaging the shaft g^2 will rotate the roller b^3 in the direction of the arrow y by means of the drive chain f^8 and 65 corresponding gears. As this operation

progresses the speed of the roller b^3 will be gradually decreased by the radial movement of the gear e^7 across the face of the gear g^2 and, of course, the movement of the roller b^2 will decrease in the same proportion as the strip or belt o and rugs o^2 are wound on the roller b^3 , and this will give a uniform or regular movement of the strip or belt o and rugs o^2 over the surface of the rock table c^3 , the longitudinal movement of the shaft e^4 by which the above operation is accomplished being effected by the operation of the crank lever d^2 as one end of the table c^3 rises and the other goes down.

When the strip or belt o and rugs are all wound on the roller b^3 and it is desired to reverse the operation of the machine, the lever k is manipulated so as to throw the wheels g and g^2 into the full line position 85 shown in Fig. 2, and at this time the gear e^7 on the shaft e^4 will be in the dotted line position shown in said figure, and will engage the gear g , and with the parts in this position the operation of the machine, as 90 above described, will result in the rewinding of the strip or belt o and rugs o^2 onto the roller b^2 , and in this operation the said rugs may be examined as they pass over the surface of the rock plate c^3 .

While we have shown and described the preferred form of our improved apparatus for exhibiting rugs, it will be understood that our invention is not limited to the details of construction herein shown and described, and various changes therein and modifications thereof may be made, within the scope of the appended claims, without departing from the spirit of our invention, or sacrificing its advantages, and we reserve 100 the right to make all such alterations therein as fairly come within the scope of the invention.

Having fully described our invention, what we claim as new and desire to secure 110 by Letters Patent, is:—

1. In a machine of the class described, a base table, rollers supported over the opposite end portions thereof, a rock table pivoted centrally over the base table and the 115 ends of which are adapted to bear on the bottoms of said rollers, shafts mounted beneath the said rollers and geared in connection therewith, friction gear wheels mounted to said shafts, and a shaft movable longitudinally of the machine and provided with friction gears adapted to engage the first named gears and to move radially thereof, and devices operated by the rock table for moving said shaft longitudinally.

2. In a machine of the class described, an oblong base or support, rollers mounted over the opposite end portions of said base or support, a flexible belt or strip wound on one of said rollers and connected with the 130

other, a rock table spring supported midway between said rollers and the ends of which are adapted to bear on the bottoms of said rollers and over which said belt or strip 5 passes, and devices in operative connection with said rock table for turning said rollers so as to wind said belt or strip on one and then rewind it onto the other.

3. In a display machine of the class described, a base, rollers supported thereover, a rock table pivoted centrally over the base and the ends of which are adapted to bear on the bottoms of said rollers, and devices

in operative connection with said rollers and said rock table for alternately turning 15 said rollers in opposite directions.

In testimony that we claim the foregoing as our invention we have signed our names in presence of the subscribing witnesses this 5th day of August, 1912.

JOHN LUTZ.
CHARLES J. LEYES.
